[57] CLAIM

The ornamental design for an inflatable bouquet, as shown.

DESCRIPTION

FIG. 1 is a front and top perspective view of an inflatable bouquet showing my new design;

FIG. 2 is a front elevational view of a petal element, shown separately for clarity of illustration, the rear being identical;

FIG. 3 is a side elevational view of FIG. 2;

FIG. 4 is a top plan view of FIG. 2; and,

FIG. 5 is a bottom plan view of FIG. 2.

FIG. 1

FIG. 4

FIG. 2

FIG. 3

FIG. 5
